UNITED STATES PATENT OFFICE.

CHARLES W. KING, OF WEST NEWTON, MASSACHUSETTS, ASSIGNOR TO
CHARLES A. KING, OF NEW YORK, N. Y.

FASTENING FOR BOOTS OR SHOES.

SPECIFICATION forming part of Letters Patent No. 392,677, dated November 13, 1888.

Application filed March 5, 1888. Serial No. 266,222. (No model.)

To all whom it may concern:

Be it known that I, CHARLES W. KING, of West Newton, county of Middlesex, State of Massachusetts, have invented certain new and useful Improvements in Fasteners for Boots and Shoes, of which the following is a specification, reference being had to the drawings accompanying and forming a part hereof, in which—

10 Figure 1 is a perspective view of my fastener. Fig. 2 is an outsole with several of my fasteners in position. Fig. 3 is a cross-section through one side of a shoe, showing my fastener between the outsole and insole in the position which it assumes when in use. Fig. 4 is a perspective showing part of an outsole fitted with a fastener.

As is well known to all skilled in the art, when a shoe has been lasted the outsole is laid 20 in position on the insole, its edges overlapping the edge of the upper, and is temporarily secured in this position preparatory to its being permanently secured by the operation of stitching or nailing. The usual method of thus temporarily securing the outsole is by means of 25 tacks or short sections of wire, which are driven through the outsole, upper, and insole at intervals around the edge of the last. These tacks are driven in the channel which is cut 30 around the edge of the outsole, in order that they may be covered up by the channel-flaps, and because it is not desirable to puncture the outer surface of the outsole, and thus interfere with the subsequent finish thereof. These 35 tacks or short sections of wire, being placed as they are in the channel, are much in the way in sewing the shoe, since the needle of the machine is frequently broken by contact with them. They also frequently remain in the 40 shoe after it is finished, and, as they project through to the inside of the insole and often work loose, they are liable to cause pain and discomfort to the wearer.

The object of my invention is to produce a 45 blind or intermediate fastener which may be inserted between the outsole and insole inside of the line of the channel of the outsole, and which shall serve to secure the outsole temporarily in position without projecting through 50 either the outsole or the insole, thus avoiding any danger of damaging the outsole or hurting the foot of the wearer; and it consists of a fastener having a single point or prong projecting in one direction and two or more divergent

curved prongs projecting in the opposite direction, as hereinafter more fully described. 55

My fastener is very simple in construction and is of substantially a Y shape, (see Fig. 1,) having a prong, *a*, projecting in one direction, and two divergent prongs, *b*, projecting in the 60 opposite direction, as shown. The base of the prong *a* is joined or secured to or is integral with the bases of the prongs *b*. A shoulder, *d*, is preferably formed around the base of the prong *a*, as shown in Fig. 1, to receive the driving tool, and thus enable the fastener to be 65 easily driven. The prongs *b* are preferably flattened, and their outer ends or points are outwardly curved, and are sufficiently sharp to permit them to be easily driven into the 70 surface of the leather. The flattening of the prongs *b* tends to prevent the fastener from working up or down when the shoe is worn.

In using my fastener, I apply it, preferably, to the flesh side of the outsole, placing the divergent prongs *b* against the sole, and driving it by a tool made for the purpose, giving it a sharp blow, which spreads the prongs *b*, forcing their ends under the surface and forcing the shanks of the prongs down against the 80 leather, thus causing the fastener to assume the position in the outsole shown in Fig. 4, the entering ends of the prongs *b* turning back toward the surface and clinching, as shown in Fig. 3. In this manner the fasteners are secured at intervals, where desired, on the outsole. the prong *a* projecting up at right angles to the surface of the sole. The outsole, being 85 thus fitted, is ready to be laid on the insole, and by a few taps of the hammer the prongs *a* are forced into the insole, (see Fig. 3,) and the outsole is firmly secured in place.

I do not desire to limit my invention to two divergent curved prongs, *b*, as obviously three, or even more, prongs, *b*, might be employed. 90

What I claim is—

A fastener for boots and shoes, having two or more divergent prongs, *b*, and a single oppositely-projecting prong, *a*, said prongs *b* being flattened and having their outward ends or points outwardly curved, and all said prongs being joined together at their bases, substantially as shown and described. 100

CHARLES W. KING.
